INKING MECHANISM FOR PRINTING MACHINES

Thomas Ewart Phythian, Leeds, and William Dudley Lawson, Branhope, near Leeds, England, assignors to R. Hoe & Co. Inc., New York, N. Y., a corporation of New York

Application July 25, 1950, Serial No. 175,672

4 Claims. (Cl. 101—365)

This invention relates to inking mechanism for printing machines: the invention is concerned with such mechanism embodying the well-known method of effecting the supply of ink by ink pumps of which a number are employed one for each section of the width of the surface to be inked: for example in newspaper printing an ink pump is usually provided for each newspaper column width of the machine.

In such apparatus it is usual for the various pumps to take their supply of ink from a common ink box, each pump delivering its individual output to individual ducts extending to an ink rail having outlets from which passes the ink for the various sections to be inked. When the multi-colour printing is to be effected it is necessary to remove ink of one colour from the box and thoroughly to clean the box, the various pumps and their associated parts and the ducts before the box is charged with ink of a different colour and various expedients have been effected to avoid this difficulty of changing the ink in an ink pump system.

Now according to the present invention an ink pump assembly comprises a number of separate self-contained ink pump units each equipped with ink pumps, an ink box from which the pumps draw their supply and with ink discharge ducts and these units are so formed that they can individually be located in position with other similar units to provide an assemblage of units which together build-up to the required width.

Thus, in a newspaper printing machine for example each unit could be arranged to supply ink for a page width of the machine and each unit would have a number of pumps one for each column width of the page: each unit would include mechanism by which the output of each pump can be individually adjusted and preferably also by means of which individual pumps can be cut-out entirely.

Provision would be made for driving the pumps of each unit and generally the arrangement would be such that the fitting of a unit into position in a machine would effect the necessary driving connection.

It will be clear that by fitting such a series of self-contained ink-pump units to a machine, selection can be made in the colour of the ink supplied by the different units: when the colour change is to be made, it is necessary merely to remove the unit or units concerned and to replace them by similar units which are charged with the particular colour required: the necessity for thorough cleaning in making colour change does not arise and moreover change can be effected very quickly by the mere act of replacement.

Printing machines for which such an inking mechanism is suitable are designed to print on webs of different widths: the present invention also makes provision whereby the self-contained ink-pump units can be made of a standard size while yet being adaptable to deal with the different widths of web: this is effected by providing loose or detachable rail plates all having discharge ducts which extend from intake openings arranged as a standard to correspond to the discharge openings formed in the

2

standard ink-pump unit, the ducts in the different plates however extending variously to discharge ends arranged to suit different widths of web.

The invention is illustrated in the accompanying drawings in which Figures 1 and 2 are respectively a plan and an end elevation of an ink pump installation and Figures 3-6 are detail views to a larger scale of an ink pump unit in accordance with this invention: Figure 3 is a sectional side elevation, Figure 4 a section on the line IV—IV Figure 3, Figure 5 a sectional elevation on the line V—V Figure 3, and Figure 6 is a sectional plan view.

Reference will first be made to Figures 1 and 2 to make clear the general arrangement of an inking mechanism according to this invention: in these figures, an inking drum or roller is indicated at 1, this roller being mounted to rotate in side frames 2, 3 and being driven by the drive of the printing machine to which ink is being supplied: this ink is fed to the roller 1 by ink pumps: one for each column width of the roller and these pumps are arranged in groups corresponding to the page width of the roller: each such group of pumps is housed in a casing four units being indicated at 4, 5, 6 and 7 and these units provide with their enclosed pumps self-contained inking units which are separately secured in position to a supporting rail 8 supported between the side frames 2, 3 each such unit including also an ink rail section by which the ink delivered by the various pumps is applied to the roller 1. Drive to the pumps inside the casings 4—7 is effected through a driving shaft 9 which is supported by brackets 10 from the rail 8 and this shaft has along its length a number of gear wheels 11 one for each ink-pump casing: each casing has an external gear wheel 12 so disposed that when the casing is fitted to the ink rail its gear 12 will automatically mesh with the appropriate gear 11 on the shaft 9 to establish drive for the pump in the casing. The driving shaft 9 is itself driven from the press-driven roller 1 through a chain drive indicated at 13.

It will be clear that, each casing 4—7 affording a self-contained ink pump unit, the various units can, when a change in colour is required for any page section of the roller 1, readily be removed and substituted by another similar unit which has been used for the fresh colour required and this is effected without requiring the elaborate cleaning which is at present necessary.

Reference will now be made to Figures 3-6 which illustrate one of the ink-pump units in detail.

Each unit comprises a box or casing 14 having a base 15 formed with a dovetailed projection 16 to locate in a dovetailed recess formed in the supporting rail 8, a pressure plate 17 operated by a bolt 18 being provided to clamp the box in position: the box is fitted with a removable cover 19 to enable it to be charged with a supply of ink and with handles 20 by which the box can be lifted.

Within the box is a series of plunger pumps 21 one for each column width and these pumps are mounted in a bar 22 which is rotatably supported at its ends eccentrically in gears 23 driven by gears 24 on a transmission shaft 25: this shaft passes out through one end wall of the box and has the gear 12 secured to it. The plungers are slideable in the bar 22 and are formed with a stop 26 to limit sliding movement in one direction and each plunger is loaded by a spring 27 to hold that stop resiliently against the bar.

The lower ends of the various plungers are slideable in bores 29 in a plate 28 which is itself free to move only with a sliding movement in the frame of its faces so that as the gears 23 are rotated, the eccentric mounting of the bar 22 causes the plungers 21 to rise and fall and also to move bodily in the transverse sense: this transverse movement carries the plate 28 to slide transversely: the arrangement is such that on the upstroke of the plungers their bores 29 move into register with a supply space 30

3

to draw ink from the box: on their down stroke their bores 29 move into register with discharge passages 31 to deliver ink thereto whence the ink is conveyed to the roller 1 through ducts 32 which extend to discharge passages 33 opening into the discharge openings 33 formed at the throat of an ink rail: this throat is formed by a flange 34 on the rail, which is indicated at 37 and by a flange 35 on a plate 36 secured to the rail 37. The output of the various pumps is regulated individually by adjustable stops 38 screwed into the cover plate 19 and operating to stop the rising or intake stroke of the individual plungers at different points, the plate 22 being permitted to continue their rising movement by the springs 27.

The discharge passages 33' and the discharge openings are formed by grooving the plate 36 at its under face: by this means it is rendered easy to adapt a standard unit to the requirements of printing on webs of different widths.

Thus, all such plates would be formed with grooves 33' having a standard pitch at their intake-end corresponding to the pitch of the supply passages 32: the grooves 33' would however diverge at different angles in different plates to discharge openings 33 arranged to suit the requirements of a particular width of web. The rail 37 is formed with a register recess to receive a register rib 39 formed on each such plate 37 which would be secured by bolts 40.

The present invention also provides means whereby the supply of ink from each plunger pump 21 (i. e. for each column width) can be shut-off without affecting the adjustment of its output as determined by the setting of the stop 38. This is effected by forming the discharge passages 31 of each plunger in a block 41 which is mounted to slide between the plate 28 and the base 15 which is formed with side guides 42 for the block 41: the ink supply space 30 is formed by recessing the face of this block, this space opening to the ink supply in the casing through an opening 43 in the plate 28. Each block 41 has an opening 44 which receives an operating disc 45 on a vertical rod 46 which extends up through the cover 19 where it is fitted with an operating handle 47. The various discs 45 are eccentrically mounted on their rods 46 so that by operation of the handles the various blocks 41 will be slid individually: in one position the discharge passages 31 will be registered with the pump bores 29 to receive ink as the plungers move down on their delivery stroke: in the other position, (i. e. the column cut-off position) the discharge passages 31 will be moved out of register with the bore 29 in all of its positions and also out of register with the discharge passage 32. In this cut-off position, each plunger 21 will take-in ink from the supply space 30 but will return it to that space on the delivery stroke.

It will be apparent that it is necessary to maintain a close sliding fit between the plate 28 and the metal in which the supply spaces 30 and the discharge openings 31 are formed: the action of the bar 22 which is maintained vertical by the fit of the plungers 21 in their bores 29 however tends to tilt the plate 28. Now, for the purpose of supporting the plate against such tilting, it is fitted with a number of upstanding posts 48 secured at their upper end to cross-heads 49 engaging under guide rollers 50 supported by the casing 14: the duty of maintaining a close sliding fit of the plate 28 is now transferred to the cross-head 49 and the rollers 50 which enable the cross-head to roll under them as the plate 28 is slid transversely.

This cross-head arrangement is preferably also employed to maintain the bar 22 and hence the plungers 21 in the vertical position: for this purpose the posts 48 are disposed in the line of the bar 22 which is formed with openings which slide snugly on the posts 48.

Thus, with this arrangement the plungers 21 are relieved of all lateral loading for they are tied by the posts to move laterally in unison with the plate 28.

What we claim is:

1. For use in a printing machine, a support, a plurality of ink supply units on the support, for supplying ink to an ink roller, and each including a casing having a series of ink conveying ducts each communicating with the roller, a plurality of ink pumps in the casing each communicating with a duct, a drive shaft on the support to operate the pumps to deliver ink to the roller, first control means to regulate the output of each of the pumps individually, second control means for each pump, independently operable to render it inoperative to pump ink through its duct, and comprising a two way valve device movable to one position to direct ink from the pump to a duct, and to another position to return ink from the pump to the casing and to close the duct, and means for quickly detaching any unit from the support and disconnecting its pumps from the drive shaft.

2. An inking mechanism for a printing machine comprising an inking roller, a support, a series of separate ink pump units each detachably mounted on the support, each unit comprising a casing having a series of ducts to convey ink to different sections of the rail, and a corresponding series of ink pumps to deliver ink to the ducts, first control means to regulate the output of each pump individually, second control means, including valves having conveniently accessible operating members, to individually stop the flow of ink from each pump to its duct, without affecting the setting of the first control means, a pump drive shaft on the support and means on each unit establishing a drive connection from the drive shaft to each of the pumps of the units.

3. An inking mechanism for a printing machine comprising an inking roller, a supporting bar having a driving shaft extending lengthwise with the roller and having gears thereon, and a series of separate ink pump units, separately and detachably secured to the bar, each unit comprising a plurality of pumps, a corresponding series of ink conveying ducts to convey ink from the pumps to different sections of the roller, first control means to regulate the output of the pumps individually, second control means including sliding block devices individually operable to stop the flow of ink from the pumps through the ducts without affecting the setting of the first control means, and an external pump driving gear on each unit positioned to engage a gear on the drive shaft.

4. An inking mechanism for a printing machine comprising an inking roller, a support having a drive shaft with gears thereon, a series of separate ink pump units to deliver ink to different longitudinal sections of the roller, each unit comprising a series of gear driven reciprocating plunger pumps having their gears engaging with, and readily separable from the gears on the drive shaft, and a corresponding series of ducts to convey ink from the pumps to different parts of a section of the cylinder, first control means to regulate the effective stroke of the pumps individually, second control means including a manually operable valve device to individually stop the flow of ink from the pumps to the ducts without affecting the setting of the first control means, and means securing the units detachably in position in the machine with their ducts positioned to discharge ink to the different parts of the roller.
